UNITED STATES PATENT OFFICE

DAVID LARKIN, OF KIRKWOOD, MISSOURI

STRAINER

Application filed May 27, 1929. Serial No. 366,431.

This invention relates to strainers, and has more particular reference to a strainer especially adapted for use in straining oils and the like.

5 An object of the invention is to provide a strainer having a diaphragm which may be readily and easily removed for cleaning.

Another object is to provide a removable supporting frame for the diaphragm to which 10 the latter may be easily applied or from which it may be easily removed and replaced.

15 A further object is to provide a supporting frame for the diaphragm which will reinforce the same against the flow of oil while at the same time offering a minimum obstruction to the flow of the oil.

20 A further object is to provide a discharge outlet which is readily accessible for the purpose of cleaning.

25 Other objects and advantages will appear in the course of the following description of a preferred embodiment of this invention.

In the accompanying drawings forming 30 part of this specification, in which like numbers of reference denote like parts wherever they occur,

Figure 1 is a vertical central sectional view of the strainer taken on the line 1—1 in Figure 2;

35 Figure 2 is an elevation of the same;

Figure 3 is a plan view with the cover partly broken away to reveal the inner structure; and

40 Figure 4 is a horizontal sectional view taken on the line 4—4 in Figure 1.

The illustrated structure comprises a casing 1, having a lateral, preferably cylindrical, wall 2 and a bottom wall 3. The lower end of the wall 2 continues below the wall 3 to 45 form supporting legs or standards 5. The upper end of the wall 2 enlarges laterally into an outer annular flange 6, and the flange 6 has an annular recess 7 in its top face for the reception of an annular flange 8 formed 50 on the under side of a cover 9 for the open top of the casing 1. Suitable packing, preferably an asbestos ring gasket 10, is interposed between the bottom face of the flange 8 and the retracted face of the recess 7. The 55 cover 9 is provided with a handle 11 for lift-

ing the same clear of the casing 1. The cover 9 is provided with laterally projecting bifurcated lugs 12, through which are adapted to pass bolts 13, pivotally connected to lugs 14, formed on the wall 2 of the casing 1 on either side of the said bolts. The bolts 13 are provided with wing nuts 15, by means of which the cover 9 is firmly fastened down in place on the casing 1.

55 A plurality of concentric vertical straining diaphragms or partitions 16 and 17 divide the casing into a plurality of concentric compartments 18, 19, and 20. The partitions 16 and 17 are supported on suitable respective supporting frames 21 and 22. The frames 21 and 22 each comprise upper and lower end members or annular plates 23, having inner and outer annular edges 24 and 25 respectively. The portion of the plates 23 adjacent the inner edge 24 are thicker than the portions juxtaposed to the peripheral edge 25, owing to an offset or shoulder 26 formed on the inner sides of the plates intermediately of the edges 24 and 25. The shoulder 26 preferably follows the periphery of a convex polygon, and a series of vertical bars 27 connects the upper and lower plates. The bars 27 are elongated in cross-section in a radial direction, being relatively thin transversely thereto, so as to afford ample resistance to 60 radially directed forces while at the same time presenting a minimum surface transversely to the flow of oil through the strainer. The outer edges 28 of the bars 27 form continuations of the edges 29 of the shoulder 26. The straining or filtering partitions 16 and 65 70 75 80 85 90 95 100

The straining or filtering partitions 16 and 17 may be formed of any suitable foraminous or porous material, preferably copper screen cloth of a mesh and size of wire suitable for the purpose of straining impurities from the oil or other fluid passed through the strainer. The screens 16 and 17 are stretched around the row of bars 27 and overlap the shoulders 26. The lower plates 23 support the straining units, on the bottom 3 of the casing, and both upper and lower plates 23 constitute means for maintaining the units in respective predetermined positions in the casing 1. The outer annular edge 25 of embracing plates 23 co-operates with the inner side 30

of wall 2 to maintain the diaphragm 17 in proper position in the casing, and the outer edge 25 of embraced plates 23 co-operates with inner edge 24 of embracing plates 23 to maintain the diaphragm 16 in its predetermined position.

The oil or other fluid to be strained is supplied to chamber or compartment 20 through a suitable pipe connection to the tapped hole 31 in the wall 2. The oil rises in the compartment 20 and filters through the screen 17 into compartment 19, rising therein and filtering through screen 16 into compartment 18, from whence it passes through an opening 32 in the bottom wall 3 into a pipe 33, preferably cast integral with the wall 3. The pipe 33 extends along the bottom of the wall 3 from one side of the strainer to the other. One end 34 of the pipe 33 is tapped for a plug 35, and the other end 36 is tapped for connection to a suitable means for leading off the oil discharged from the strainer through the opening. The sediment and impurities settle to the bottom of the compartments 18, 19, and 20, and do not clog the openings in the screens 16 and 17. When sufficient sediment has collected, the cover 9 may be removed and the sediment removed. The pipe 33 may be easily cleaned or flushed by removing the plug 35 to provide access thereto. It will be observed that the bars 27 reinforce the screens 16 and 17 against the rush of oil thereagainst. The bars 27 may be cast integral with the plates 23, or they may be soldered thereto, or may be fitted and secured in slots in the said plates.

Having thus fully described this invention, I hereby reserve the benefit of all changes in form, arrangement, order, or use of parts, as it is evident that many minor changes may be made therein without departing from the spirit of this invention or the scope of the following claims.

I claim:

1. In a strainer, a straining unit comprising a pair of annular end plates of the same shape and dimensions, said plates having arcuate inner and outer edges, the plates having opposed shoulders at their inner faces, the inner edges of said shoulders being arcuate and flush with the inner edges of the plates, the outer edges of the shoulders being polygonal in plan, bars connected with the vertices of the shoulders and bridging the space between the plates and straining material surrounding the series of bars and attached at its edges to the polygonal edges of the shoulders.

2. In a strainer, a straining unit comprising a pair of annular end plates of the same shape and dimensions, said plates having arcuate inner and outer edges, the plates having opposed shoulders at their inner faces, the inner edges of said shoulders being arcuate and flush with the inner edges of the plates,

the outer edges of the shoulders being polygonal in plan, bars connected with the vertices of the shoulders and maintaining the plates in spaced relation and straining material surrounding and being supported by the series of bars and attached at its edges to the polygonal edges of the shoulders.

In testimony whereof I hereunto affix my signature.

DAVID LARKIN. 75
